UNITED STATES PATENT OFFICE.

JOSHUA H. MARVIL OF V. AND ISAAC H. DOWNS, OF LAUREL, DELAWARE, ASSIGNEES
OF ONE-THIRD TO JOSHUA D. MARVIL AND TWO-THIRDS TO SIRMAN D. MARVIL,
BOTH OF LAUREL, DELAWARE; SALLIE L. MARVIL AND FRANK B. SIRMAN,
EXECUTORS OF SAID JOSHUA D. MARVIL, DECEASED.

BLOW-OUT PATCH.

1,102,938.

Specification of Letters Patent.

Patented July 7, 1914.

Application filed December 13, 1913. Serial No. 306,507.

To all whom it may concern:

Be it known that we, JOSHUA H. MARVIL of V. and ISAAC H. DOWNS, citizens of the United States, residing at Laurel, in the county of Sussex and State of Delaware, have invented new and useful Improvements in Blow-Out Patches, of which the following is a specification.

Our present invention relates to improvements in repair patches for pneumatic tires, and the primary object is to provide an inexpensive device of this character which is capable of being easily and quickly applied and which will protect the inner tube from blowing out through the outer casing or from being injured by contact with a broken or weakened portion of the casing, the patch, according to the present invention, being substantially in the form of a bandage which is wrapped around the tube, it being so shaped that it avoids the formation of an abrupt shoulder which would tend to chafe and injure the tube, and it has an adhesive so applied as to prevent creeping or displacement of the patch as well as to retain the convolutions thereof in proper position.

To these and other ends, the invention consists in certain improvements, and combinations and arrangements of parts, all as will be hereinafter more fully described, the novel features being pointed out particularly in the claims at the end of the specification.

In the accompanying drawings:—Figure 1 is a side elevation of a portion of an inner tube of a pneumatic tire having a repair patch embodying the present invention applied thereto—Fig. 2 represents a longitudinal section through the portion of the tube and the repair patch as shown in Fig. 1; Fig. 3 represents a transverse section through a tire equipped with a repair patch embodying the present invention; Figs. 4, 5 and 6 are perspective views of repair patches embodying the present invention; Fig. 7 represents a transverse section through a tire equipped with a repair patch constructed as shown in Fig. 6. Fig. 8 is a side elevation of a portion of a tube fitted with a repair patch of the construction shown in Fig. 6.

Similar parts are designated by the same reference characters in the several views.

Repair patches embodying the present invention are capable of use in connection with a pneumatic tire of any form using an inner inflatable tube. In Figs. 4, 5 and 6, three different forms of patches are shown. In Fig. 4, the patch embodies a band 1 composed of inelastic flexible material such for example as canvas, or canvas and rubber. The band tapers from one end toward the other, that is to say, its longitudinal edges converge in order that when the thicker end of the band is applied to the tube and the thinner end is wrapped about the tube in convolutions, the patch will have its greatest width next to the tube and will diminish in width outwardly, overlapping of the edges of the patch being thereby avoided and the ends of the patch will be beveled or will slope from its outermost to its innermost convolution. This feature enables the patch to conform readily to the shape of the tube and casing and it avoids a sharp or abrupt shoulder at each end of the patch; hence chafing of the tube at these points is avoided. This characteristic of the patch is shown in Figs. 5 and 6 also. In Fig. 4, a relatively thicker section 2 is stitched or otherwise fastened to the wider or inner end of the band, this section of the patch being adapted to substantially encircle the tube and to cover the blow-out, weakened or broken portion of the casing, it being understood that the tapering band is wrapped or wound over this section. An adhesive substance, such as rubber cement, is preferably applied to the outer or narrower end of the band and at that side thereof which lies against the inner convolutions of the band whereby when the band has been wound upon the tube this adhesive will prevent loosening of the convolutions. Such an arrangement is shown in Fig. 5, the narrower end of the band in that figure having the adhesive 3 applied thereto.

In Fig. 6, the patch comprises a widened or body section 4 which is adapted to be so applied to the inner tube as to cover the weakened or broken portion of the casing, and a flap 5 extends from one edge of this body section while a band 6 extends from

the opposite edge thereof, the band 6 diminishing in width as it proceeds from the body section 4. The patch in this instance is preferably composed of a flexible inelastic fabric such as canvas or canvas and rubber, and one side of the fabric has an adhesive applied thereto, such for example as rubber cement. In applying a patch of this type, the widened body section 4 is fitted to the tube in a position where it will cover the weakened or broken portion of the casing, the adhesive side of the band being outermost and the flap 5 is folded substantially at the edge where it joins the body section 4 so as to lie against the adhesive side thereof, thus providing a reinforcement to prevent blowing of the tube into the weakened or broken portion of the casing. The band 6 is then wound about the tube and over the flap 5 and as each convolution of the band is wound upon the tube the adhesive on the outer side of the band will unite the convolutions and retain them in place. Also, when the tube having the patch applied thereto is placed in the casing and the tube is inflated, the adhesive on the outer surface of the patch will be presented to the wall of the casing and will become firmly united thereto, thereby preventing creeping or movement of the patch within the tire. In Figs. 3 and 7, 7 designates the outer cas-

ing, 8 the inner tube, and 9 the wheel rim to which the tire is applied.

What is claimed is:—

1. A repair patch for pneumatic tires comprising a blow-out covering section, a flap extending from one side thereof, and a band extending from the opposite side thereof and diminishing in width in a direction from said section toward its free end. 35

2. A repair patch for pneumatic tires comprising a blow-out covering section, a flap extending from one side thereof, a band extending from the opposite side thereof, and an adhesive applied to one side of said section and band. 45

3. A repair patch for pneumatic tires comprising a blow-out covering section, a flexible band extending therefrom, one side of said section and band being adhesive, 50 and a flap smaller in dimensions than said section and extending from an edge of said section and foldable upon the adhesive side thereof.

In testimony whereof we have hereunto set our hands in presence of two subscribing witnesses.

JOSHUA H. MARVIL QF V.

ISAAC H. DOWNS.
